BOWLING LANE MAINTENANCE MACHINE

Patrick J. Regan, Elm Grove, Wis., assignor to D.B.A.
Products Company, Inc., Deerfield, Ill., a corporation
of Illinois

Filed Aug. 7, 1961, Ser. No. 66,216

Term of patent 14 years

(Cl. D9—2)

Fig. 3.

Fig. 4

Fig. 5.

FIGURE 1 is a perspective view taken from one side of a bowling lane maintenance machine showing my new design;

FIGURE 2 is a top plan view showing the top side of the machine;

FIGURE 3 is an elevational view showing the rear side of the machine;

FIGURE 4 is a side elevational view taken to show one side of the machine; and

FIGURE 5 is a side elevational view showing the opposite side of the machine.

The dominant features of the design reside in the portions shown in full lines.

I claim:

The ornamental design for bowling lane maintenance machine, substantially as shown and described.
